[57] **CLAIM**

The ornamental design for a compartmented storage box for stationery articles or the like, as shown and described.

DESCRIPTION

FIG. 1 is a front perspective view of a compartmented storage box for stationery articles or the like showing my new design;

FIG. 2 is a right side elevational view thereof;

FIG. 3 is a bottom plan view thereof;

FIG. 4 is a rear elevational view thereof;

FIG. 5 is a perspective view thereof from above and the rear showing the lid open; and

FIG. 6 is a view similar to FIG. 5 but showing the compartments in alternative positions.

FIG.1

FIG.2

FIG. 3

FIG. 4

FIG.5

FIG.6
